UNITED STATES PATENT OFFICE.

GEORGE H. MILLER, OF BROOKLYN, NEW YORK.

ANNUNCIATOR.

1,329,920.

Specification of Letters Patent.

Patented Feb. 3, 1920.

Application filed March 19, 1919. Serial No. 283,593.

To all whom it may concern:

Be it known that I, GEORGE H. MILLER, a citizen of the United States, and residing at Brooklyn, in the county of Kings and State of New York, have invented certain new and useful Improvements in Annunciators, of which the following is a specification, such as will enable those skilled in the art to which it appertains to make and use the same.

This invention relates to annunciating apparatus designed to be used in connection with street cars, elevated and subway cars, and cars of electric and steam railway systems as well as other power driven passenger vehicles, and which is designed to indicate by signs or other means the various stops or stations that the car or train makes in its route, or in traveling from one place to another; and the object of the invention is to provide an apparatus of the class and for the purpose specified which is pneumatically operated and which is provided with means or devices for controlling the operation of the apparatus; a further object of the invention being to provide means whereby said apparatus may be operated by the usual air compressor or compressed air apparatus employed in connection with cars or trains of the class specified; and a still further object of the invention being to provide an apparatus of the class and for the purpose specified which is simple in construction and operation and efficient in use.

The invention is fully disclosed in the following specification, of which the accompanying drawings form a part, in which the separate parts of my improvement are designated by suitable reference characters in each of the views, and in which:

Figure 1 is a diagrammatic transverse sectional view of the top portion of a railway car and indicating the method of mounting my improved apparatus in connection therewith;

Fig. 2 a diagrammatic side view of the apparatus detached and indicating the method of its use;

Fig. 3 is a sectional plan view of a part of the apparatus shown in Fig. 2, the section being on the line 3-3 of said figure;

Fig. 4 a partial section on the line 4-4 of Fig. 3; 55

Fig. 5 a view similar to Fig. 4 but showing only a detail of the construction and on an enlarged scale;

Fig. 6 a partial section on the line 6-6 of Fig. 4 and on an enlarged scale; 60

Fig. 7 a partial section on the line 7-7 of Fig. 2 on an enlarged scale and indicating a part of the car in connection with which the apparatus is mounted;

Fig. 8 a view similar to Fig. 7 but showing other details of the construction in section; 65

Fig. 9 a section on the line 9-9 of Fig. 7;

Fig. 10 a section on the line 10-10 of Fig. 7; and 70

Fig. 11 a partial section on the line 11-11 of Fig. 2 and on an enlarged scale.

In Figs. 1, 7, and 8 of the drawing I have indicated at 11 a part of the car of a railway system. In Fig. 1 I have shown at 12 a part of the side walls of said car, a top 13, a supplemental top 14 and an interior frame or supporting structure 15, and at 16 I have shown the annunciator casing in which is mounted the members for announcing or designating the names of the streets, stations or stops to be made by the car 11, and at 17 I have indicated a keyboard or a governor box provided with devices adapted to control the movement of the announcing or designating members in the casing 16. 75

The casing 16 is approximately rectangular in form and opens upwardly and downwardly, as clearly shown in Figs. 3 and 4, and secured to the side walls 18 are angle iron strips 19 connected at their opposite ends with flat strips 20 secured to the opposite ends of the casing, and the corner portions of the strips 19 and 20 are also secured to, or are provided with upwardly directed angle iron extensions 21, having ears 22 extending at right angles thereto through which may be passed screws, bolts 100 or similar devices for connecting the same with suitable corner brackets 23 used in supporting the casing 16 on the interior framework 15 of the car as is illustrated in Fig. 1 of the drawing. 105

Each of the angle iron strips 19, or the

top horizontal portions thereof is provided at spaced intervals with upwardly directed screws or threaded pins 24 with which are detachably connected transverse plates 25, six of which are shown in Fig. 3, and one of which is shown in Figs. 4 and 5, and in the construction shown the angle iron strips 19 are adapted to support ten of the plates 25.

The plates 25 are each constructed in the same manner and are provided centrally thereof with a raised portion 26 to which is secured a cylinder 27 packed as shown at 28. Mounted in the cylinder 27 is a piston 29 and a piston rod 30, the rod 30 passes through the lower end of the cylinder 27 and through a bore 31 in the plate 25. The upper end of the cylinder 27 is closed by a cap 32 with which is connected a pipe 33, while a similar pipe 34 is connected at one side of the bottom portion of the cylinder 27, as clearly shown in Fig. 5 of the drawing, and a pipe coupling 35 is mounted in the pipe 34 adjacent to the upper end portion of the cylinder 27.

I also employ a plurality of card supporting casings 36, the number of which will correspond with the number of plates 25 employed, and said casings are adapted to detachably support printed or otherwise designated cards 37 which are passed into said casing through an open end 38 therein. The top central portion of said casings are connected with the lower end portions of the piston rods 31 through a bridge construction 39, as clearly shown in Figs. 4 and 5, and at the top of each of the casings and adjacent to the opposite end portions thereof are secured vertical guide rods 40 which extend upwardly through the plates 25, as clearly shown in Figs. 3 and 4, and tensional devices 41 are connected with the plates 25 and operate in connection with said rods and serve to aid in holding the casings 36 in their raised or normal position.

The above description sets out the details of construction of the casing 16 and the various parts connected therewith, and in Figs. 2 and 7 to 10 inclusive, I have shown the detail construction of the keyboard or governor box 17, said box comprising an approximately oblong and rectangular case 42, which opens inwardly and which is connected with a back plate 43 in any desired manner. The back plate 43 is provided with a plurality of forwardly directed sleeve members 44, ten of which are employed in the construction shown and which are arranged in series of fives, one above another, as shown in Fig. 2. Each of the sleeve members 44 are provided with two intake pipes 45 and 46, and two discharge pipes 47 and 48, the intake pipes 45 and 46 being connected with a main horizontal distributor pipe 49 through vertical branch pipes 50. An air supply 51 is con-

nected with the distributor pipe 49 approximately, centrally thereof, and said pipe is also connected with any sort of supply, namely, an air compressor or a compressed air tank usually employed in vehicles of the class to which this invention relates, said apparatus being not shown for the reason that it forms no part of this invention.

The discharge pipes 47 and 48 from each of the sleeve members 44 extend upwardly and are connected with the pipes 33 and 34 respectively, or in any desired manner, or the pipes 33 and 34 may be the same as the pipes 47 and 48 but may be continuous.

The front of the casing 42 is provided with a plurality of apertures 52 which correspond in number and which are in line with the bores of the sleeve members 44, and passed through the apertures 52 and mounted in the cylinders 44 are valve members 53 retained in, but rotatably mounted in the sleeve members 44 by a pin and slot construction shown at 54 in Fig. 7 of the drawing. The protruding faces of the valves 53 are provided with key slots or openings 55, whereby a suitable key may be employed for rotating said valves. The valves 53 are each provided with two transverse bores 56 and 57 as well as two radial bores 58 and 59, and the latter communicate with the transverse bores centrally thereof, as clearly illustrated in Figs. 9 and 10 of the drawing. The sleeve members 44 are also provided with two discharge apertures 60 and 61 arranged at the opposite sides thereof and in vertical alignment with the discharge pipes and intake pipes 45 and 47, 46 and 48 respectively.

In the normal position of the valves 53 in which position the casings 36 are held in their raised position or within the casing 16, the bores 56 and 58 are in the position shown at the top of Fig. 9, in which position of the valves the air through the intake pipes 45 is shut off and said bores form a communication between the discharge pipes 47 and the discharge apertures 60 in the sleeve members 44. In this position of the valves, the bores 57 and 59 are in the position shown at the top of Fig. 10 and in this position the intake and discharge pipes 46 and 48 are placed in communication by the transverse bores 57 to permit air to pass through the valves 53 upwardly into the bottom portions of the cylinders 27 and serve to hold the pistons 29 in their raised positions as shown in full lines in Fig. 5 of the drawing.

When the valves 53 are turned into their operative position by a suitable key, as is indicated in the lower lefthand corner of Fig. 2 of the drawing, and as is shown at the bottom of Figs. 7 to 10 inclusive, the bores 56 and 58 are moved into the position shown at the bottom of Fig. 9 in which position the bore 56 places the intake and dis-

charge pipes 45 and 47 in communication to admit air to pass upwardly through the discharge pipe 47 into the top of the cylinder 27 through the pipe 33 to move the 5 piston 29 in said cylinder downwardly thus moving the casing 36 of said cylinder downwardly into the position shown in Figs. 2 and 4, it being understood that the particular valve 53 operated will operate the casing 10 36 connected with the cylinder 27 placed in communication with said valve through the pipes 47 and 48 of said valve.

For the purpose of utilizing a particular apparatus of the class specified for various 15 purposes, or for cars the routes of which vary from day to day, or at different times, the valves 53 are consecutively numbered and, in the construction shown, said valves are numbered from 1 to 10, and a suitable 20 index or keyboard 62 shown in Fig. 2 of the drawing is located adjacent to the box 17, or in connection therewith. The index or keyboard 62 is divided, in any desired manner, into a plurality of spaces 63 which correspond in number to the number of valves 53 employed, and these spaces are consecutively 25 numbered as shown at 64 to correspond with the numbering of the valves 53, and the streets, stations and stops on a particular 30 route are arranged in the spaces 63 of the index or keyboard 62, as shown at 65, and the cards 37 with the street, station or stop titles thereon are correspondingly arranged 35 in the casings 36 so that, for example, when "Wall St." is the next stop of the train or car in connection with which my apparatus is employed, the operator will insert a key 40 in the valve 53 numbered 6, said operator receiving directions from the index or keyboard 62 and the corresponding casing 36 will be lowered by compressed air in the manner above set out.

The operation of returning the casing 36 moved downwardly by the rotation of the 45 valve numbered 6, as above set out, will be performed by returning the valve to its normal position by the key employed, in which operation air will pass upwardly through the discharge pipe 48 and into the 50 bottom of the cylinder 27 through the pipe 34, while the air in the top of said cylinder and the pipes 33 and 47 will be discharged downwardly and outwardly through the discharge aperture 60 in the sleeve member 44.

A valve 66 is mounted in a downwardly directed extension 67 of the case 42 or in a sleeve member 68 similar to the sleeve members 44, said valve being similar in construction to the valves 53 and provided in the face thereof with a key slot 69 and with a single transverse bore 70, which operates in connection with the supply pipe 51 which connects with the top and bottom portions 65 of the sleeve member 68, as clearly shown in

Fig. 11, and is adapted to control the supply of air to the distributing pipe 49.

It will be understood that my improved apparatus may be constructed in any desired manner, and while I have shown but 70 ten valves 53 and a corresponding number of casings 37, my invention is not limited to any specific number of said valves or said casings, ten of these being merely shown to illustrate the apparatus and the method 75 of its operation; and further it will be understood that while I have shown various details of construction for carrying my invention into effect, I am not necessarily limited to these details, and changes therein 80 and modifications thereof may be made, within the scope of the appended claims, without departing from the spirit of my invention or sacrificing its advantages.

Having fully described my invention, what 85 I claim as new and desire to secure by Letters Patent, is:—

1. In an apparatus of the class described, a casing, a plurality of independent designating members movably mounted in said 90 casing, and means for pneumatically operating each of said members.

2. In an apparatus of the class described, a casing, a plurality of independent designating members movably mounted in said 95 casing and normally retained therein, valve devices placed in communication with each of said members, and means whereby the operation of one of said devices will pneumatically operate one of said members to 100 project it from said casing.

3. An annunciator apparatus for passenger cars, comprising a casing mounted in said car, a plurality of designating members movably mounted in said casing and normally retained therein, a plurality of valve devices mounted in the car at a predetermined distance from said casing and each of which are placed in communication with one of said members, and means whereby 110 the operation of one of said valve devices will operate the member in communication therewith to project the same from said casing.

4. In an apparatus of the class described, 115 a casing, a plurality of cylinders mounted in said casing, a corresponding number of designating members mounted in said casing and in operative connection with said cylinders, and means for passing compressed 120 air into and out of each of said cylinders to operate said members.

5. In an apparatus of the class described, 125 a casing, a plurality of cylinders mounted in said casing, a corresponding number of designating members movably mounted in said casing and in operative connection with said cylinders, a plurality of valve devices placed in communication with said cylinders, and means whereby the operation of 130

said valve devices will move said members in said casings.

6. In an apparatus of the class described, a casing, a plurality of cylinders detachably mounted in said casing, a corresponding number of designating members movably mounted in said casing, pistons connected with each of said members and adapted to operate in said cylinders, a plurality of 10 valve devices, pipes for placing said valve devices in connection with said cylinders, means for supplying compressed air to said valve devices, and means whereby the operation of said valve devices will admit air 15 to said cylinders to move the pistons therein and to correspondingly operate the members with which said pistons are connected.

7. In an apparatus of the class described, a casing, a plurality of cylinders detachably mounted in said casing, a corresponding number of designating members movably mounted in said casing, pistons connected with each of said members and adapted to operate in said cylinders, a plurality of 20 valve devices, pipes for placing said valve devices in connection with said cylinders, means for supplying compressed air to said valve devices, means whereby the operation of said valve devices will admit air to said 25 cylinders to move the pistons therein and to correspondingly operate the members with which said pistons are connected, and means whereby sign elements may be detachably connected with said members.

8. In an apparatus of the class described, a casing, a plurality of cylinders mounted in said casing, a corresponding number of designating members movably mounted in said casing, pistons connected with each of 40 said members and adapted to operate in said cylinders, means for guiding said members in their movement in said casing, means for holding said members normally within the casing, a plurality of valve devices the 45 number of which correspond with the number of cylinders in said casing, pipes communicating with each of said valve devices and with each of said cylinders, means for supplying compressed air to said valve devices, and means whereby the operation of 50 said valves will supply compressed air to said cylinders through said pipes to operate the pistons in said cylinders and project said members beyond said casing.

9. In an apparatus of the class described, a casing, a plurality of cylinders mounted in said casing, a corresponding number of designating members movably mounted in said casing, pistons connected with each 60 of said members and adapted to operate in said cylinders, means for guiding said members in their movement in said casing, means for holding said members normally within the casing, a plurality of valve devices the 65 number of which correspond with the num-

ber of cylinders in said casing, pipes communicating with each of said valve devices and with each of said cylinders, means whereby the operation of said valves will supply compressed air to said cylinders 70 through said pipes to operate the pistons in said cylinders and project said members beyond said casing, and means for controlling the supply of compressed air to said valve devices. 75

10. In an apparatus of the class described, a casing, a plurality of cylinders mounted in said casing, a corresponding number of designating members movably mounted in said casing, pistons connected with each of 80 said members and adapted to operate in said cylinders, means for guiding said members in their movement in said casing, means for holding said members normally within the casing, a plurality of valve devices the number of which correspond with the number of cylinders in said casing, intake pipes communicating with each of said valve devices, discharge pipes communicating with said valve devices, said discharge pipes being also 85 placed in communication with said cylinders, means for supplying compressed air to the intake pipes of said valve devices, means for controlling said supply of air, and means whereby the operation of said 90 valve devices will admit air to said cylinders to move the pistons therein and to operate said members. 95

11. In an apparatus of the class described, a casing, a plurality of cylinders mounted 100 in said casing, a corresponding number of designating members movably mounted in said casing, pistons connected with each of said members and adapted to operate in said cylinders, means for guiding said members in their movement in said casing, means for holding said members normally within the casing, a plurality of valve devices the number of which correspond with the number of cylinders in said casing, intake pipes 105 communicating with said valve devices, discharge pipes communicating with said valve devices, said discharge pipes being also placed in communicating with said cylinders, means for supplying compressed air 110 to the intake pipes of said valve devices, means for controlling said supply of air, means whereby the operation of said valve devices will admit air to said cylinders to move the pistons therein and to operate said 115 members, and means for designating each of said valve devices to distinguish one from the other. 120

12. In an apparatus of the class described, a casing, a plurality of cylinders mounted 125 in said casing, a corresponding number of designating members movably mounted in said casing, pistons connected with each of said members and adapted to operate in said cylinders, means for guiding said members 130

in their movement in said casing, means for holding said members normally within the casing, a plurality of valve devices the number of which correspond with the number 5 of cylinders in said casing, intake pipes communicating with each of said valve devices, discharge pipes communicating with said valve devices, said discharge pipes being also placed in communication with said 10 cylinders, means for supplying compressed air to the intake pipes of said valve devices, means for controlling said supply of air, means whereby the operation of said valve devices will admit air to said cylinders to 15 move the pistons therein and to operate said members, means for designating each of said valve devices to distinguish one from the other, and means whereby sign elements 20 may be detachably connected with each of said members.

13. In an apparatus of the class described, an annunciator casing open at the top and bottom, a plurality of plates detachably mounted in the top portion of said casing, 25 cylinders connected with each of said plates, pistons movably mounted in said cylinders, card casings mounted in the bottom portion of said casing and in operative connection with said pistons, said casings being normally contained within the casing, and means for supplying compressed air to said 30 cylinders to operate said pistons to move said card casings outwardly and inwardly in said casing.

14. In an apparatus of the class described, an annunciator casing open at the top and bottom, a plurality of plates detachably mounted in the top portion of said casing, cylinders connected with each of said plates, 40 pistons movably mounted in said cylinders, card casings mounted in the bottom portion of said casing and in operative connection with said pistons, said casings being normally contained within the casing, means 45 for supplying compressed air to said cylinders to operate said pistons to move said card casings outwardly and inwardly in said casing, means for guiding said card casings in their movement in said casing, and tensional 50 devices for holding said card casings normally in a raised position.

15. In an apparatus of the class described, an annunciator casing open at the top and bottom, a plurality of plates detachably 55 mounted in the top portion of said casing, cylinders connected with each of said plates, pistons movably mounted in said cylinders, card casings mounted in the bottom portion of said casing and in operative connection 60 with said pistons, said casings being normally contained within the casing, means for supplying compressed air to said cylinders to operate said pistons to move said card casings outwardly and inwardly in 65 said casing, means for guiding said card

casings in their movement in said casing, tensional devices for holding said card casings normally in a raised position, and means whereby sign cards may be detachably connected with said casings. 70

16. In an apparatus of the class described, a keyboard or governor box, a plurality of valve devices rotatably mounted therein, each of said valve devices being provided with a pair of bores and a pair of intake 75 and discharge pipes communicating with each of said valve devices.

17. In an apparatus of the class described, a keyboard or governor box, a plurality of valve devices rotatably mounted therein, 80 each of said valve devices being provided with a pair of bores and a pair of intake and discharge pipes communicating with each of said valve devices, and means whereby said valve devices may be rotated to bring 85 the pair of bores therein in communication with said pairs of intake and discharge pipes.

18. In an apparatus of the class described, a keyboard or governor box, a plurality of 90 valve devices rotatably mounted therein, each of said valve devices being provided with a pair of bores and a pair of intake and discharge pipes communicating with each of said valve devices, means whereby said valve 95 devices may be rotated to bring the pair of bores therein in communication with said pairs of intake and discharge pipes, a distributor pipe placed in communication with each pair of said intake pipes, and means 100 for supplying compressed air to said distributor pipe.

19. In an apparatus of the class described, a keyboard or governor box, a plurality of valve devices rotatably mounted therein, 105 each of said valve devices being provided with a pair of bores and a pair of intake and discharge pipes communicating with each of said valve devices, means whereby said valve devices may be rotated to bring the pair of bores therein in communication with said pairs of intake and discharge pipes, a distributor pipe placed in communication with each pair of said intake pipes, means 110 for supplying compressed air to said distributor pipe, and means for controlling the supply of compressed air to said distributor pipe.

20. In an apparatus of the class described, 120 a keyboard or governor box, a plurality of valve devices rotatably mounted therein, each of said valve devices being provided with a pair of bores and a pair of intake and discharge pipes communicating with each of said valve devices, means whereby said valve 125 devices may be rotated to bring the pair of bores therein in communication with said pairs of intake and discharge pipes, a distributor pipe placed in communication with each pair of said intake pipes, means 130

for supplying compressed air to said distributor pipe, means for controlling the supply of compressed air to said distributor pipe, and means for marking each of said 5 valve devices for distinguishing one from another.

In testimony that I claim the foregoing as

my invention I have signed my name in presence of the subscribing witnesses this 15th day of March, 1919.

GEORGE H. MILLER.
